UNITED STATES PATENT OFFICE

133,799

DESIGN FOR A TABLETING MACHINE

Keith W. Hall, Toledo, Ohio, assignor to Defiance
Machine Works, Inc., Defiance, Ohio, a cor-
poration of Ohio

Application January 3, 1942, Serial No. 105,012

Term of patent 14 years

To all whom it may concern:

Be it known that I, Keith W. Hall, a citizen of the United States, residing at Toledo, in the county of Lucas and State of Ohio, have invented a new, original, and ornamental Design for a Tableting Machine, of which the following is a specification, reference being had to the accompanying drawing forming a part thereof.

In the drawing:

Fig. I is a front perspective view of a tableting machine showing my new design; and,

Fig. II is a rear perspective view thereof.

I claim:

The ornamental design for a tableting machine, as shown.

KEITH W. HALL.
